UNITED STATES PATENT OFFICE

MARY C. HENNESSY, OF NEW YORK, N. Y., ASSIGNOR TO FRANKLIN SIMON & COMPANY, INC., OF NEW YORK, N. Y., A CORPORATION OF NEW YORK

COMBINED BRASSIÈRE AND STEP-IN

Application filed June 25, 1932. Serial No. 619,299.

This invention relates to garments and particularly to an improved combination brassière and step-in, the object being to provide a garment of this kind which will take the place of all under-garments including corsets.

Another object of the invention is to provide an improved combination brassière and step-in wherein the same is formed with 10 elastic front and rear sections and elastic side sections so positioned as to provide a desired constriction of the body at the waistline and over the hips without interfering with the movement of the body.

15 A further object of the invention is to provide a combined step-in and brassière which will resiliently hug the sides of the body and which presents hose supporting means so that the garment may act in the 20 capacity of a supporting structure for hose.

In the accompanying drawing,—

Figure 1 is a perspective view of a combined brassière and step-in disclosing an embodiment of the invention, the same being 25 illustrated on a figure.

Figure 2 is a front view of the device shown in Figure 1, the same being on a slightly enlarged scale.

Figure 3 is a rear view of the device shown 30 in Figure 2.

Figure 4 is a sectional view through Figure 2 on line 4—4.

Figure 5 is a detail fragmentary enlarged 35 view of part of one of the elastic sections illustrating the net formation of the elastic.

Referring to the accompanying drawing by numerals 1 indicates the front section of the panel and 2 the rear section of the panel connected by side sections 3 and 4. The 40 front and rear sections are made from some desirable cloth which is substantially inelastic, while the side sections 3 and 4 are made of a fabric embodying vulcanized latex threads, the same being an elastic netting which is sufficiently strong to constrict 45 somewhat the waistline and hips without producing an undesired pinching action, and by reason of its open mesh permit a desired circulation of air.

50 From Figures 1 and 2 it will be seen that

the respective front and rear sections are constricted respectively at 5 and 6 so that at the waistline there is a wider portion of the elastic members 3 and 4 than at other points. This is clearly illustrated at 7 in Figure 4. It will be understood that the elastic members 3 and 4 are of identical shape so that the illustration in Figure 4 will illustrate both of the members.

55 A crotch structure 8 is provided having sections 9 and 10 secured together by suitable means, as, for instance, a button and buttonhole structure 11. A brassière section 12 is provided with elastic pockets 13 and 14 with separating panels 15, 16 and 17 from the front 1 whereby proper support is provided. At the back, the brassière section 12 is preferably provided with a rounded edge 18 which is somewhat lower in the front.

60 Connected to the step-in section 19 are suitable hose supporters 20 whereby the device will take the place of a corset as well as a brassière and panties.

65 While it is possible to use the garment without the shoulder straps 21, these are desirable to cause the breast pockets 13 and 14 to function properly without causing an undesirable constriction.

70 The front and rear sections 1 and 2 are preferably inelastic, as above set forth, but the elastic side sections 3 and 4 are yieldable in all directions, and, therefore, permit the body to twist and turn readily to take any posture without injuring the garment or unduly resisting the action of the person. 75 However, when a person is standing substantially erect, as shown in Figure 1, there is only a slight constriction at the hips, and, if desired, there may be substantially no constriction at the waistline, though, ordinarily, 80 a snug fitting and slightly constricting size is preferable. It will be understood that in each garment the same is of a certain size and is preferably adapted to a particular sized person, though slightly different sized 85 persons may use the same garment without discomfort.

90 In order to readily get into the garment the brassière section 12 is divided along the line 22, while suitable snap fasteners, such as 95

hooks and eyes, or other disengageable fastening means, are used to normally hold the parts together. When it is desired to remove the device, the hose supporters 20 are disengaged and the brassière is opened along line 22. The shoulder straps 21 are then removed from the shoulders and the device may be readily forced down over the hips. To again don the device a reverse action takes place.

I claim:—

1. A garment of the character described including front and rear inelastic sections constricted substantially centrally, and a pair of side elastic sections connected to the front and rear inelastic sections, said elastic sections diverging as they approach the waistline so as to have their widest portion at the waistline, and means forming with the center of the front and rear sections at their lower ends a step-in structure at the lower part of the garment while the upper part of the garment merges into a brassière structure.
2. A garment of the character described comprising a front inelastic section, the sides of which are concave with the narrowest portion positioned at the waistline, breast pockets inserted in the upper part of said front section, a rear section of substantially the same shape as the front section and formed of inelastic material, a pair of side elastic sections diverging as they approach the waistline to fit said front and rear sections, and disengageable means connecting the front and rear sections at their bottom edges and forming with said sections and the side sections a step-in structure.
3. A garment of the character described comprising a front inelastic section the sides edges of which are concave with the narrowest part of the section at the waistline of the garment, a rear inelastic section of substantially the same shape as the front section, said front section having a pair of cut out portions at the top, breast pockets positioned in said cut out portions, and a pair of elastic openwork side sections substantially diamond shaped at the upper part with the widest portion at substantially the waistline and merging into curved sides at the lower end.

MARY C. HENNESSY.
